UNITED STATES PATENT OFFICE.

STANLEY BROWN, OF GARDEN CITY, NEW YORK, ASSIGNOR TO THE GRISCOM BUSH-SELL COMPANY, OF NEW YORK, N. Y., A CORPORATION OF DELAWARE.

COMBINED EVAPORATOR AND FEED-WATER HEATING SYSTEM.

Application filed January 26, 1920. Serial No. 353,998.

To all whom it may concern:

Be it known that I, STANLEY BROWN, a citizen of the United States, residing at Garden City, in the county of Nassau, State 5 of New York, have invented certain new and useful Improvements in Combined Evaporator and Feed-Water Heating Systems; and I do hereby declare the following to be a full, clear, and exact description of 10 the invention, such as will enable others skilled in the art to which it appertains to make and use the same.

This invention relates to combined evaporator and feed water systems for power and 15 industrial plants and for use on shipboard where a large quantity of impure or raw water must be evaporated to maintain a pure water supply for boiler feed and industrial purposes.

20 In large power plants, whether on shipboard or in central stations or industrial establishments, the power is usually developed by compound engines or turbines, the returns from which are a condensate of low, 25 pressure and low temperature well below the atmospheric boiling point of 212 degrees F. In many establishments the quantity of low temperature condensate is not over 85% of the total requirements for the boiler feed, 30 due to various losses in auxiliary apparatus, and the use of the main boiler steam for various industrial purposes. This deficit is supplied by the evaporation of impure water in evaporators utilizing steam from 35 the main boilers as the heating fluid, and in order for the plant to be economically run it is necessary that the heat thus diverted from the main boiler to the evaporators be returned to the system in the condensed steam used in the evaporator and the vapor from the evaporators, and it has heretofore been the custom to utilize the condensed steam and vapor from the evaporators in feed water heaters for both the 40 evaporator feed and the main boiler feed, the condensed steam and vapor from all 45 sources being returned to a large open heater from which the boiler feed is pumped.

It is the purpose of the present invention to provide a plant of this general character in which the heat from the evaporator plant shall be returned to the system as far as possible in the boiler feed heater, thus allowing the more expensive condensers

necessary for feed water heaters to be of 55 low cost and small capacity.

In the accompanying drawing I have illustrated diagrammatically a typical power plant arrangement embodying my invention.

Referring to the drawing, 1 and 2 indicate the two effects of a typical evaporator plant to which the raw water to be evaporated is fed through a feed pipe 3 and the heating fluid or steam from the main boilers is fed from the steam main by a pipe 4 to 65 the coils of the first effect of the evaporator. The vapor from the first effect passes through the vapor line 5 to the coils of the second effect and the condensate from the coils is discharged through the usual traps 70 to a common discharge line 6.

The vapor from the second effect is discharged through the vapor line 8 to the feed heater 7 which serves as a condenser for the 75 vapor, the condensate from which is piped through the main return line 9 to the plant heater 10, a suitable trap being interposed in the line to prevent the discharge of vapor to the heater. Water pumped from the 80 heater 10 through the heater 7 takes up the heat from the vapors which enter the said heater 7.

The feed heater 7 is at a lower pressure than the drains in the line 6 from the coils of the evaporators, consequently a portion 85 of the heat from the drain line may be used in the feed heater by providing a trap 20 in the drain line 6 with a riser 11 in advance of the trap and leading to the feed water heater 7 so that the "flash" represented by 90 the difference in temperature between the drain line and the vapor in the feed water heater will be formed in the riser and condensed in the feed water heater in the manner described in my copending application Serial No. 353,999 filed concurrently herewith which has matured into Patent 1,400,385, December 20, 1921. A valve 11^a is 95 preferably provided in the riser 11 so that all of the coil drains may be forced to pass 100 into the boiler feed heater 10, if desired.

The boiler-feed heater receives the exhaust steam from the various auxiliary apparatus of the plant and also the low temperature condensate from the engines of the main power plant through the pipe 12, this condensate being normally at a comparatively low temperature of about 80-100 degrees.

This condensate furthermore ordinarily occurs in sufficient quantity so that the latent heat contained in the vapor issuing from the evaporators, and also the heat of the exhaust steam, may be completely absorbed in the boiler feed heater 10 without raising the temperature of the water contained in the heater to such an extent that boiling will result. Where a large amount of heat is extracted in the feed water heater 7, the temperature in the plant heater 10 may be considerably below 212 degrees F., at which temperature it may with perfect safety be maintained. In order to maintain the heater 10 at 212 degrees under such circumstances so that the auxiliary feed water heater 7 may be kept of as small size as possible, I may draw off part of the vapor from the vapor line 8 through a pipe 13 directly to the open heater, and provide a valve in the pipe 13 for checking the flow of vapor through the pipe 13, when the temperature in the boiler-feed heater 10 rises above boiling point.

For the purpose of illustration I have shown an ordinary automatic back pressure valve 14 having a diaphragm chamber 15 connected to the heater 10 through a pilot pipe 16, the valve being set to cut off the flow of vapor through the pipe 13 upon the development of any pressure in the heater. As the pressure in the heater is normally considerably less than that in the feed water condenser, the vapor will flow in the pipe 13 to the full capacity of the back pressure valve and consequently will always tend to maintain the heater 10 at the highest temperature (and corresponding pressure) for which the valve is set.

The invention of this application is particularly useful where there is a changing load on the power plant which produces variations in the relative quantity of vapor and auxiliary steam to be condensed and the condensate from the main engines. For instance, in central stations the boiler make-up required and the auxiliary steam used is comparatively constant while the load on the main engines varies greatly. By the arrangement here shown the boiler feed heater 10 will be prevented from receiving a supply of steam in excess of that required to maintain it in operation at its maximum pressure and temperature conditions, inasmuch as the heat contained in the auxiliary steam will not ordinarily be excessive. In case the heat returns to the heater 10 are deficient, the regulating valve 14 will serve to admit additional steam to the open heater and tend to maintain it in operation at the proper temperature. If any regulating means are provided for controlling the quantities of vapor delivered to the heater 10 the plant has to be designed so that under the conditions of operation when the quantity of vapor and steam to be condensed is

greatest in proportion to the quantity of low temperature condensate the boiler-feed heater will not be raised above atmospheric boiling point. Hence, at normal load conditions the heater 10 will be at an unnecessarily low temperature.

It is desirable to maintain the temperature of the boiler-feed heater 10 at about the atmospheric boiling point for two further reasons. First, the turbine condensate, and in some cases the condensed evaporator vapor, contain entrained gases. These gases are much better relieved at 212 degrees than at lower temperatures. In the second place, the surface condensers employed for condensing the exhaust steam from the main engines are seldom absolutely tight so that there is frequently a sucking in of a small portion of the impure water used as condensing means. The impure solid content so brought in is passed to the power plant heater and the higher the temperature of the heater the better will be the cracking out, or, depositing, of such impurities.

It will of course be understood that various changes may be made in the arrangement of the apparatus. For instance, a portion of the vapor from the line 8 may be used in a feed water heater for the evaporators; or a second feed water heater may be used in series with the heater 7 in the manner shown in my co-pending application above referred to, the gist of the present invention being the arrangement hereinafter claimed for maintaining the boiler-feed heater 10 at its maximum temperature.

I claim:

1. In a power plant system, the combination of a boiler feed heater at relatively low pressure for receiving the returns from the steam-utilizing apparatus of an evaporator plant for making up the fluid loss from the power plant system, means for condensing the vapor from said evaporator system comprising a condenser, the pressure in said condenser being appreciably higher than that in said boiler feed heater, a vapor line leading thereto, and a branch from said vapor line to said heater, and means controlled by the temperature of the heater for regulating the quantity of vapor delivered through said branch line for maintaining said heater at a predetermined temperature.

2. In a power plant system, the combination of a boiler feed heater for receiving the returns from the steam-utilizing apparatus of an evaporator plant for making up the fluid loss from the power plant system, means for condensing the vapor from said evaporator system comprising a second feed water heater maintained at a pressure appreciably above that of said boiler feed heater for heating the water from said heater, a vapor line leading to the vapor space of said second heater, and a branch

from said vapor line to said boiler-feed heater, and means controlled by the temperature of said heater for regulating the quantity of vapor delivered through said branch line for maintaining said heater at a predetermined temperature.

3. In a power plant system, the combination of a boiler feed heater for receiving the return from the steam-utilizing apparatus, an evaporator system for making up the liquid losses from said power system, and means for conserving the heat in the discharge from said evaporator comprising a second feed water heater maintained above atmospheric pressure for heating the water from said boiler feed heater, a vapor line from said evaporator to the vapor space of said second heater, a branch from said vapor line to the boiler feed heater, and an automatically operating valve in said branch line and a regulator therefor controlled by the temperature of said boiler feed heater to maintain the temperature of the heater at approximately atmospheric boiling temperature.

4. In an evaporator system, means for condensing the vapor therefor comprising a condenser maintained at a pressure above atmospheric and a boiler feed heater, an automatically actuated regulator adapted to admit to said heater sufficient steam to maintain the temperature of said heater at approximately atmospheric boiling point and cause the remainder of the steam from said evaporator system to flow into said condenser.

5. In an evaporator system, the combination of an evaporator unit, a condenser, a boiler feed heater, a vapor line leading from the evaporator unit to the condenser and a branch leading to the said heater, and means for regulating the flow of vapor through said branch comprising a valve, and a regulator therefor controlled by the temperature of the liquid in the heater and adapted to admit to said heater sufficient steam to maintain the temperature of said heater at approximately atmospheric boiling point and cause the remainder of the steam from said evaporator system to flow into said condenser.

6. In a power plant system, the combination of a boiler feed heater for receiving the condensed returns from steam utilizing apparatus and also for receiving unden- 55 sioned steam or vapor from such apparatus, a condenser for condensing a portion of such steam or vapor, a by-pass around the condenser from the vapor line to the heater 60 and a valve in said by-pass controlled by

the temperature of the heater for admitting to said heater a quantity of steam sufficient to maintain the temperature of said heater at approximately atmospheric boiling point.

7. In a system of the class described, a boiler feed heater for receiving the returns from the steam utilizing apparatus, evaporators for supplying purified water to said system, a condenser maintained at relatively high pressure through which water from said boiler feed heater is passed before admission to the boiler, a vapor line from said evaporators to said condenser, whereby the vapor output of said evaporators is condensed and the latent heat of the vapor imparted to the boiler feed water, means for conveying condensate from said condenser into said boiler feed heater, and means for admitting the discharge from the heating elements of said evaporators to said heater.

8. In a system of the class described, a boiler feed heater for receiving the returns from the steam utilizing apparatus, evaporators for supplying purified water to said system, a condenser maintained at relatively high pressure through which water from said boiler feed heater is passed before admission to the boiler, a vapor line from said evaporators to said condenser, whereby the vapor output of said evaporators is condensed and the latent heat of the vapor imparted to the boiler feed water, and means for transmitting to the boiler feed water the contained heat in the drains from said condenser and in the discharge from the heating elements of said evaporators.

9. In a system of the class described, a boiler feed heater for receiving the returns from the steam utilizing apparatus, evaporators for supplying purified water to said system, a condenser maintained at relatively high pressure through which water from said boiler feed heater is passed before admission to the boiler, a vapor line from said evaporators to said condensers whereby the vapor output of said evaporators is condensed and the latent heat of the vapor imparted to the boiler feed water, means for subjecting the drains from the heating elements of said evaporators to a reduced pressure, whereby a portion of said drains will be vaporized by reason of their contained heat, means for conducting the vapor thus formed into said condenser, means for conveying the liquid portion of said drains into the boiler feed heater, and means for conveying condensate from said condenser into said heater.

In testimony whereof I affix my signature.
STANLEY BROWN.
